RAILWAY TRAFFIC CONTROLLING
APPARATUS

Carl G. Harwig, Wilkinsburg, Pa., assignor to The
Union Switch & Signal Company, Swissvale,
Pa., a corporation of Pennsylvania

Application February 8, 1935, Serial No. 5,601

5 Claims. (Cl. 246—46)

My invention relates to railway traffic controlling apparatus, and particularly to automatic signaling apparatus of the type involving light signals. More specifically, my invention relates to a means for providing an additional indication on a light signal.

In the usual automatic block signaling system, the signals are spaced at the maximum braking distance of the trains governed by such a system. The signals usually provide for three indications, namely, proceed, approach (prepare to stop at next signal) and stop. When it is desired to increase the traffic capacity of a railway equipped with such a system, the signals necessarily have to be spaced less than braking distance so that the trains may follow each other more closely. When this is done an additional indication has to be provided so that the speed of the trains will be properly regulated upon approaching a stop signal. One object of my invention is to provide a signal capable of displaying four indications, and also to provide simple and reliable means for controlling each of the four indications. I shall term the fourth indication "approach medium" which indicates to an approaching train, "approach next signal at not exceeding medium speed." Since the next signal, as I shall explain hereinafter, will be displaying the "approach" indication, the advancing train will pass such signal at medium speed and, therefore, will be able to stop if the signal next in advance is displaying a stop indication.

Other objects of my invention will become apparent as the specification progresses.

I will describe two forms of railway traffic controlling apparatus embodying my invention, and will then point out the novel features thereof in claims.

In the accompanying drawing, Fig. 1 is a diagrammatic view illustrating one form of railway traffic controlling apparatus embodying my invention. Fig. 2 is a diagrammatic view illustrating another form of such apparatus also embodying my invention.

Similar reference characters refer to similar parts in each view.

Referring first to Fig. 1, the reference character Z designates a stretch of railway track along which traffic normally moves in the direction indicated by the arrow. The rails I and IA of stretch Z are divided, by means of insulated joints 2, into a plurality of successive track sections A—B, B—C, C—D, and D—E. Each such track section is provided with a track circuit. Each such track circuit is provided with a source of cur-

rent, here shown as a battery 3, connected across the rails at the leaving end of the section, and with a track relay designated by the reference character T with a suitable distinguishing suffix corresponding to the location and connected across the rails at the entrance end of the section.

Located adjacent the entrance end of each section is a signal designated by the reference character J with a distinguishing suffix and here shown as a light signal comprising four units; namely, a green lamp G, a red lamp R, and two yellow lamps Y and Y2. When the green lamp G is lighted, the signal indicates "proceed"; when the yellow lamp Y is lighted, the signal indicates "approach medium", that is, "approach next signal at medium speed"; when both yellow lamps Y and Y2 are lighted, the signal indicates "approach", that is, "prepare to stop at next signal"; and when the red lamp R is lighted, the signal indicates "stop".

It will be noted, when lamps Y and Y2 of a particular signal are both lighted, that such lamps are connected in series and, therefore, a source of double voltage will be required to light these lamps. I have provided each signal with such a source which is here shown as an auto-transformer designated by the reference character P with a suitable distinguishing suffix corresponding to the location. It is understood, of course, that any other source of increased voltage sufficient to light two such lamps in series may be used instead of the transformer P, such, for example, as a battery having twice the number of cells required for lighting one of the lamps.

It will also be apparent that, due to lamps Y and Y2 being connected in series, neither lamp will be lighted if the other is burned out or otherwise defective, when traffic conditions are such as to cause display of the "approach" indication. If lamps Y and Y2 were connected in multiple, one of the yellow lamps could be lighted with the other burned out which might cause the signal to display the "approach medium" indication instead of the "approach" indication. My invention, therefore, prevents the display of a less restrictive indication in the event that one of the yellow lamps should be defective.

I shall describe the circuits and operation for signal JA only since signals JB, JC, and JD are controlled and operated in a manner similar to that which will be described for signal JA.

The red lamp R is provided with a circuit which passes from terminal X of a suitable source of alternating current, through back contact 4 of track relay TA and lamp R to terminal O of the

same source of current. Thus, it will be seen that lamp R will be lighted only when relay TA becomes released, that is, when section A—B is occupied.

- 6 The yellow lamp Y is provided with a circuit which passes from terminal X through back contact 5 of track relay TC, front contact 6 of track relay TB, front contact 7 of track relay TA and lamp Y to terminal O. Thus, lamp Y will be 10 lighted only when section C—D is occupied and relay TC becomes released provided section A—B and B—C is each unoccupied.

The green lamp G is provided with a circuit which passes from terminal X through front contact 15 8 of track relay TC, front contact 9 of track relay TB, front contact 10 of track relay TA and lamp G to terminal O. Lamp G, therefore, will be lighted only when sections A—B, B—C, and C—D are all unoccupied and relays TA, TB and 20 TC are all energized.

The yellow lamp Y2 in series with lamp Y is provided with a circuit which includes the secondary winding 11 of auto-transformer PB and front contact 12 of track relay TA. The primary 25 winding 13 of transformer PB is connected to terminal O permanently, and to terminal X through back contact 14 of track relay TB. Thus, it will be seen that primary 13 will become energized only when section B—C is occupied and relay TB becomes released, and that when relay TB is released, lamps Y and Y2 will each be lighted 30 provided section A—B is unoccupied.

From the foregoing description it is now apparent that signal JA will indicate successively 35 "stop", "approach", "approach medium" and "clear" in rear of a train moving in the direction of the arrow and occupying sections A—B, B—C, C—D, and D—E, respectively, in succession. Such train, therefore, will be fully protected against 40 a following train.

Referring now to Fig. 2, the track Z has been divided into the usual track sections A—B, B—C, and C—D. Section B—C and C—D is each provided with a track circuit including a battery 3 45 and a track relay designated by the reference character T with a suitable distinguishing suffix. Section B—C and C—D is each also provided with a signal designated by the reference character H with a suitable distinguishing suffix. Each signal is here shown as a color light signal comprising 50 three lamps, namely, a green lamp G, a yellow lamp Y and a red lamp R.

Section A—B, however, has been further divided by insulated joints 2 into section A—A1 55 and A1—B. The track relay TA is connected across the rails of section A—A1 and a track relay TA1 is connected across the rails of section A1—B, each such section being provided with a track battery 3. The section A—B is provided 60 with a signal HA which has a yellow lamp Y2, in addition to the usual green lamp G, yellow lamp Y, and red lamp R.

Associated with track relay TA1 is an auto-transformer PA1 which at times, as will be explained hereinafter, is effective for energizing the 65 two yellow lamps Y and Y2.

Since signals HB and HC are the usual three indication automatic signals controlled in the well-known manner, I will explain the control 70 and operation of signal HA only.

The red lamp R of signal HA is lighted only when track relay TA is released and back contact 15 of this relay becomes closed; therefore, signal HA displays the stop indication only when section 75 A—A1 is occupied by a train.

The two yellow lamps are connected in series by a circuit which includes front contact 16 of track relay TA and secondary 17 of the auto-transformer PA1. The primary 13 of transformer PA1 is energized only when back contact 19 of track relay TA1 becomes closed, that is, when section A1—B is occupied. Thus, the two yellow lamps Y and Y2 of signal HA are both lighted when section A1—B is occupied and section A—A1 is unoccupied, so that a following train may occupy section A—A1. I shall term this indication a "closing-in" indication since it permits two trains to occupy section A—B at the same time. Such an indication may be used at points where it is desired to facilitate and hasten the loading and 10 unloading of passengers, such, for example, as at and near station platforms.

The yellow lamp Y is provided with a circuit comprising front contact 20 of track relay TA, front contact 21 of track relay TA1 and back contact 22 of track relay TB. Thus, signal HA displays the usual approach indication only when relay TA and TA1 is each energized and relay TB is deenergized, that is, when sections A—A1 and A1—B are unoccupied and section B—C is occupied.

The green lamp G is lighted only when relay TA, TA1 and TB is each energized and front contact 23, 24, and 25, respectively, is each closed; therefore, signal HA displays the proceed indication only when section A—A1, A1—B, and B—C is each unoccupied.

From the foregoing description of the two forms of my invention illustrated in Figs. 1 and 2, it will be seen that I have provided a simple 35 and reliable means for securing a fourth indication on a signal which indication may be employed in an automatic block signaling system for regularly displaying a fourth indication at all signals of such a system, or may be employed at 40 special locations as a "closing-in" signal. My invention also provides a means for insuring that, in the event each of the two yellow lamps do not become lighted, one yellow lamp may not be lighted and cause the display of a misleading 45 and less restrictive indication. It will be noted that all relays employed in my invention are track relays, therefore, my invention provides the four indications, hereinbefore described, without 50 the use of line relays.

Although I have herein shown and described only two forms of apparatus embodying my invention, it is understood that various changes and modifications may be made therein within 55 the scope of the appended claims without departing from the spirit and scope of my invention.

Having thus described my invention, what I claim is:

1. In combination, a section of railway track, a signal for said section comprising a red lamp and a yellow lamp as well as a green lamp, means for lighting said red lamp when one particular portion of said section is occupied by a train, means for lighting said yellow lamp when only a 65 certain zone in advance of said section is occupied, means for lighting said green lamp when said section and such certain advance zone are both unoccupied, another yellow lamp on said signal, and means for lighting both of said yellow lamps when another particular portion of said section is occupied by a train and such one particular portion is unoccupied.
2. In combination, a stretch of railway track divided into a plurality of track sections, a plu- 75

rality of signals one for each section each such signal comprising a red lamp and a green lamp as well as a pair of yellow lamps, means for energizing the red lamp at each signal when a particular section in advance of the associated signal is occupied by a train, a series circuit for each pair of yellow lamps, means for energizing each such circuit when only another particular section in advance of the associated signal is occupied, means for energizing one yellow lamp of each signal when only still another particular section in advance of the associated signal is occupied, and means for energizing the green lamp of each signal when each such section in advance of the associated signal is unoccupied.

3. In combination, a stretch of railway track divided into three track sections each such section having a track circuit including a track relay, a signal for said stretch comprising a red lamp and two yellow lamps as well as a green lamp, a source of current, a circuit connecting said source with said red lamp and including a back contact of the track relay of the first section in advance of said signal, a circuit connecting both of said yellow lamps with said source and including a front contact of the track relay for the first section as well as a back contact of the track relay for the second section in advance of said signal, a circuit connecting said source with one of said yellow lamps and including a front contact of the track relay for the first section as well as a front contact of the track relay for the second section and a back contact of the track relay for the third section, and a circuit for said green lamp including a front contact of each such track relay.

4. In combination, a stretch of railway track divided into two sections, a first and a second track circuit each including a track relay for the first section and a third track circuit including a track relay for the second section, a signal for said stretch comprising a red lamp and two yellow lamps as well as a green lamp, a circuit for said red lamp including a back contact of the track relay for the first track circuit, a circuit for both of said yellow lamps including a front contact of the track relay for the first track circuit and a front contact of the track relay for the second track circuit, a circuit for one of said yellow lamps including a front contact of the track relay for the first track circuit and a front contact of the track relay for the second track circuit as well as a back contact of the track relay for the third track circuit, and a circuit for said green lamp including a front contact of each such track relay. 5 10 15

5. In combination, a forward section and a rear section as well as an intermediate section of railway track, a track circuit including a track relay for each section, a signal including a first lamp and a second lamp, a transformer, a circuit for said first lamp including a back contact of the track relay for the forward section as well as a front contact of each of the track relays for the intermediate and rear sections, and a circuit connecting said two lamps in series and including said transformer as well as a back contact of the track relay for the intermediate section and a front contact of the track relay for the rear section. 20 25 30 35

CARL G. HARWIG.
